RADIATOR CLEANING COMPOSITION

Benjamin Gallsworth, Glenham, N. Y., assignor
to The Texas Company, New York, N. Y., a
corporation of Delaware

No Drawing. Application August 27, 1934,
Serial No. 741,741

4 Claims. (Cl. 87—5)

This invention relates to a radiator cleaning compound adapted to be added to the circulating water of a radiator of an internal combustion engine, for the purpose of removing accumulated 5 rust, dirt and scale and increasing the co-efficient of heat transfer of the radiator shell and cylinder block.

Various types of radiator cleaning compositions of this character have heretofore been suggested, but have been in the main either comparatively ineffective for the purpose or else objectionable as dangerous to use because of chemical attack upon the metal parts of the circulating system, solder, hose connections and the like. 10 Such compositions have generally been in the form of dry powders to be added to the circulating water, or concentrated water solutions. While having some beneficial effect upon deposited scale or dirt, such materials are generally 15 ineffective in removing the scum of deposited oil which accumulates in a radiator of this character. In order to remove such an oily scum, a petroleum fraction of the character of kerosene has been employed. However, it has proved difficult to secure an effective mixture of kerosene 20 with a cleaning compound, in order to secure the desired easy handling and addition of the materials to a radiator for effective distribution therein. 25 It is an object of the present invention to provide a radiator cleaning composition of this character which is effective in removing both scale and oily scum without objectionable action upon materials of the circulating system, and to provide 30 the composition in a highly effective form which can be easily handled and directly added to the circulating water so as to obtain maximum efficiency.

In accordance with the present invention the 35 radiator cleaning composition is a concentrate in the form of a water-oil emulsion containing a cleaning compound and an emulsifying agent. The oil employed is preferably a kerosene fraction. Various types of alkali metal cleaning 40 compounds can be employed, which are of a character to effect desired removal of rust, scale and dirt and at the same time avoid injury to the metal and rubber parts of the circulating system. A very satisfactory material of this character is 45 sodium metasilicate. However, ordinary water glass or other alkali metal or soluble silicates can be employed. Likewise, trisodium phosphate or other alkali metal phosphates can be used.

An emulsifying agent, preferably in the form 50 of an alkali metal soap, is employed to form a

permanent or semi-permanent emulsion of the water, kerosene and alkali metal cleaning compound. Various alkali metal soaps or triethanolamine soaps can be used for this purpose. But, preferably, an alkali metal soap of acids of oxidized waxy hydrocarbons is employed as constituting a highly effective and economical emulsifying agent. A very satisfactory material of this character is obtained by forming the alkali metal soap of acids of oxidized paraffin wax, the latter being prepared as disclosed in my U. S. Patent No. 1,909,945. As set forth in the patent, a charge of paraffin wax, for example crude scale wax having a gravity of between 48° and 50° A. P. I. at 130° F., is placed in an enameled or aluminum vessel which is preferably jacketed or otherwise fitted to permit heating or cooling of the contents. The vessel is also fitted with an air distributor, preferably located near the bottom, through which air may be introduced in fine streams to promote intimate contact of the air with the oxidizing mass. If the vessel is well insulated, the heat developed by the oxidation will be sufficient to maintain the charge at the proper temperature, once it has been brought to that temperature by outside means such as a steam coil. The charge of wax may be heated to a temperature between 260° and 335° F. and air may be introduced in sufficient quantity to maintain the desired temperature. The most satisfactory temperature range for the oxidation has been found to be about 315°—320° F. The oxidation is allowed to proceed until the batch attains a gravity of 33°—35° A. P. I. By carrying out the oxidation in this manner, a material is produced having a low acid value while containing a relatively large amount of saponifiable bodies or esters. Moreover, the oxidized material is substantially free from red gum, which is that material insoluble in naphtha, for example an 86° Bé gasoline. The resulting oxidized material is then subjected to sweating at 90°—100° F. and separated into approximately $\frac{2}{3}$ of semi-liquid sweatings and $\frac{1}{3}$ of solid waxy material. The sweatings so obtained had approximately the following tests:

Gravity, °Bé	25.5
Viscosity at 100° F.	205 S.U.
Pour, °F.	95
Neutralization No	25.8 50
Saponification No	129

The following is an example of the preparation of a radiator cleaning composition of this invention, utilizing the oxidized paraffin wax sweatings

obtained as above outlined. The following ingredients were heated together at around 180° F. for 7 hours, with occasional stirring:

	Grams	Percent by weight
Oxidized paraffin wax sweatings.....	600	60
Sodium hydroxide 95 percent.....	40	4
Water.....	360	36

10 The mixture lost 247 g. in weight during the above saponification which left it with the following approximate composition:

	Grams	Percent by weight
Oxidized paraffin wax sweatings.....	600	79.68
Sodium hydroxide 95 percent.....	40	5.31
Water.....	113	15.00

15 500 g. of this impure sodium soap of oxidized paraffin wax acids, prepared as outlined above, was then mixed at 180° F. with 1000 g. of water. 20 The mixture was then allowed to stand and stratify into 2 layers. The top layer, amounting to about 20% by volume and consisting mainly of unsaponifiable waxes, was removed from the bottom layer of soap solution, while the material 25 was still warm (about 120° F.). To this soap solution was added about 10% by weight of sodium metasilicate, and the material agitated until the metasilicate dissolved. Approximately 30 75% by weight of this soap solution containing the metasilicate was then agitated in a high speed 35 stirrer with 25% by weight of kerosene, until a good emulsion was obtained which showed little signs of separation after standing 1 week.

40 The above concentrate in the form of an emulsion has many advantages in ease of handling and in effectiveness as a radiator cleaner. In use, the concentrate may be poured directly into a large volume of water in the circulating system, whereupon with running of the engine, a dilute 45 emulsion is formed throughout the circulating system. For example, about 1/2 to 3 pounds of the concentrated emulsion may be added to approximately 2-3 gallons of circulating water to give an effective cleaning action. The radiator engine 50 may be run for about 30 minutes, and then the radiator drained and flushed. Or, if desired, the cleaning composition may be allowed to remain

over night in the radiator, which is then drained and flushed. The proportions in which the ingredients of the composition can be employed and the strength of the concentrate, can be varied within wide limits; and it is to be understood that the above is given by way of example and not by way of limitation.

Obviously many modifications and variations of the invention, as hereinbefore set forth, may be made without departing from the spirit and scope thereof, and therefore only such limitations should be imposed as are indicated in the appended claims.

1 I claim:

15 1. A radiator cleaning composition consisting essentially of a preformed concentrated emulsion of water in kerosene containing a soluble silicate and the sodium soap of acids of oxidized paraffin wax, the composition being adapted to be added directly to the circulating water of an internal 20 combustion engine cooling system to form a dilute emulsion of cleaning effectiveness therewith.

2. A radiator cleaning composition consisting essentially of a preformed concentrated emulsion of water in kerosene containing sodium metasilicate and the sodium soap of acids of oxidized paraffin wax, the composition being adapted to be added directly to the circulating water of an internal combustion engine cooling system to form a dilute emulsion of cleaning effectiveness there- 30 with.

3. A radiator cleaning composition comprising a preformed concentrated emulsion consisting of about 75% by weight of a sodium soap of oxidized paraffin wax sweatings in solution in about twice 35 the weight of water of the said sweatings, and containing about 10% by weight of sodium metasilicate on the weight of the said soap solution, together with about 25% by weight of kerosene.

4. The method of forming a radiator cleaning 40 composition, which consists of mixing an alkali metal soap of oxidized paraffin wax acids with water, dissolving therein an alkali metal silicate, and then emulsifying the said solution with kerosene to produce a preformed concentrated stable 45 emulsion which is adapted to be added in said emulsified condition directly to the circulating water of an internal combustion engine cooling system to form a dilute emulsion of cleaning effectiveness therewith.

BENJAMIN GALLSWORTHY.
